UNITED STATES PATENT OFFICE.

HANS GROSSER, OF BUENOS AIRES, ARGENTINA, ASSIGNOR TO THE FIRM UNITED STATES IMPORT HOUSE EMANUEL VAN DAM, OF AMSTERDAM, NETHERLANDS.

PRINTING APPARATUS FOR PRINTING INDIARUBBER BALLOONS IN AN INFLATED CONDITION.

Application filed March 3, 1927, Serial No. 172,518, and in Germany April 8, 1925.

The printing apparatus forming the subject-matter of the present invention renders it possible to print in one single operation or process upon all sides of indiarubber balloons, bladders or other inflatable articles when they are in an inflated condition.

Hitherto it has only been possible to print indiarubber balloons partially, by spreading them out flat in an uninflated condition or 10 to inflate them and to place the balloons on the usual printing press and to print in the usual manner and stamping them, a process which precluded the possibility of printing them on all sides, and which in consequence 15 of the distortion occurring upon inflation of the indiarubber balloon, only admitted of being used for a large or bold style of ornamentation or lettering.

The apparatus according to the present 20 invention is illustrated by way of example in the accompanying drawings in sectional elevation, Figure 1 showing it in an open condition and Figure 2 in a closed condition.

The apparatus consists of two hollow 25 hemispheres, the internal surfaces *a* and *b* of which form or carry the printing blocks *d*, and which can be separated from one another, as shown in Figure 1, for the purpose 30 of enabling the uninflated balloon *c* to be introduced, and then brought together to form a closed sphere, as shown in Figure 2.

The method of operation of the apparatus is as follows:—

After the internal or printing-block sides 35 *d* of the two hollow hemispheres *a* and *b* have been inked, the latter are closed round the uninflated balloon *c* to form a hollow sphere. By means of compressed air the balloon *c* is so strongly inflated that it presses 40 with its entire surface against the printing-block walls *d* and accordingly receives an impression therefrom. After the balloon *c* has diminished in size owing to the discharge of part of the air enclosed therein, 45 the hemispheres *a*, *b* are opened again for the purpose of being inked afresh, and the printed balloon is removed.

The inking of the printing blocks or print-

ing block walls *d* may be effected either by hand or by means of mechanical appliances. 50

By this printing apparatus for printing indiarubber balloons it is possible to print by one single process or by one single operation all sides or parts around such balloons. 55

In the above specification the new printing apparatus has been described and illustrated by way of example as consisting of two hollow hemispheres *a* and *b*, but it will be obvious that the new printing mold provided with the printing blocks or surfaces *d* may consist of more than two parts for instance the mold may consist of 12 parts, which work together in the same way as described 60 and show the shape of a closed sphere consisting of 12 parts (like an orange) if brought together, without departing from the nature of the present invention. 65

What I claim is:—

1. Printing apparatus for printing upon 70 indiarubber balloons and the like, comprising a hollow mold capable of being opened for the introduction of the balloon in an uninflated condition, the internal cavity of said mold, when closed, being substantially of the same shape as the balloon when inflated, said mold being formed with a small aperture through which the mouth of the balloon can pass for inflating purposes, and printing surfaces upon the interior of said mold. 80

2. Printing apparatus for printing upon indiarubber balloons and the like, comprising a hollow mold capable of being opened for the introduction of the balloon in an uninflated condition, the internal cavity of 85 said mold, when closed, being substantially of the same shape as the balloon when inflated, said mold being formed with a small aperture through which the mouth of the balloon can pass for inflating purposes, and concave printing blocks adapted to be fitted into the interior of said mold. 90

In testimony whereof I have signed my name to this specification.

HANS GROSSER.
